BUNDLE TYING MACHINE FEEDER AND THE
CONTROL MECHANISMJulian J. Eberle, Wauwatosa, Wis., assignor to
The Journal Company, Milwaukee, Wis., a cor-
poration of Wisconsin

Application December 28, 1948, Serial No. 67,716

13 Claims. (Cl. 100—4)

1

This invention relates to a bundle tying machine feeder and the control mechanism.

Broadly, it is the object of the invention to provide an accessory device for the automatic delivery of bundles to a tying machine or the like, the said device including means for correlating the action of the tying machine or the like with the functioning of such device to the end that all operations may be effected automatically and mechanically. The bundle tying machine or the like may be of any conventional construction and reference thereto is intended to include, from the standpoint of the broad invention here involved, machines other than bundle tying machines specifically. No modification of any structure of any such machine is intended or required for the purposes of the present invention.

More specifically, one of the objects of the invention is to provide a conveyor system which includes a number of units, some of which act impositively upon the work to permit work to accumulate thereon, awaiting its turn for delivery to the tying or other machine. At the same time, the conveyor system includes other elements with sufficiently positive action to assure the correct positioning of the bundles or other work respecting the machine which is to act thereon, and also preferably adapted to push from such machine work which has previously been acted upon thereby. In effectuating these objectives, I propose to use conveyor elements which include some that are continuously operable and others that are intermittently operable, together with means for coordinating their various operations with each other and with the operation of the bundle tying or other machine.

It is a further purpose of the invention to provide a feeder and control mechanism which is readily adaptable for the delivery of successive bundles or other workpieces in single stage movement through the machine which is to act thereon or, alternatively, to move such bundles or other workpieces through the said machine in a succession of stages. This phase of the invention has particular utility in connection with bundle tying machines where it may be desired, in some instances, to make a single tie centrally of the bundle and, in other instances, to make two or more ties at spaced intervals about each bundle. In the latter case, it is a specific object of the invention to provide means for adjusting the thrust of the bundle propelling mechanism upon the bundle, according to the stage at which it is being propelled into or through the machine, it being found that a bundle which has already had

2

one tie requires much less thrust for its subsequent movement than a bundle as yet untied. The present device is adapted automatically to vary the thrust according to the condition of the work in this regard.

Still other objects of the invention will be more apparent in the light of the following disclosure thereof.

In the drawings:

10 Fig. 1 is a general view in perspective of the association of a feeder and a tying machine in a combination exemplifying the invention, the tying machine being diagrammatically illustrated.

15 Fig. 2 is a view in vertical section through the feeder and contiguous portions of the tying machine.

Fig. 3 is a view taken in horizontal section in the plane indicated at 3—3 in Fig. 2.

20 Fig. 4 is a view taken in horizontal section on the line 4—4 of Fig. 2.

Fig. 5 is a view taken in transverse section on the line 5—5 of Fig. 3.

25 Fig. 6 is a fragmentary detail view on an enlarged scale showing partially in section and partially in side elevation one of the cam mechanisms illustrated in Fig. 2.

Fig. 7 is a view in perspective showing a single tied bundle on a reduced scale.

30 Fig. 8 is a view in perspective showing on a reduced scale a bundle having the first of two ties.

Fig. 9 is a view similar to Fig. 8 showing the bundle completed with two ties.

35 Fig. 10 is a simplified wiring diagram for the controls of the feeder.

Fig. 11 is a table of switch positions for the control of the various operations of the feeder.

It is the general object of the invention to deliver the bundles 1 from the conveyor 2 to the tying machine as rapidly as the bundles are supplied and the tying machine is able to operate thereon, any excess number of bundles deposited at irregular intervals upon the conveyor being stored thereon, and the tying machine and the intervening feeder generically designated by reference character 4 being mechanically synchronized as to operation.

In order that the conveyor 2 may operate both as a supply conveyor and as a means of storing excess bundles, I employ a conveyor at this point which includes a frame 6 having sprocket means 7 for the laterally disposed chains 8, 9 (Fig. 3). These chains are cross connected by the rods 10 upon which are journaled rollers 11 on which

rest the bundles or other workpieces to be propelled or stored. Means not shown is provided, as usual, for driving one of the sprocket means about which the conveyor chains 6, 9 are guided. If there is no resistance to forward movement of the bundles, these will move with the upper run of the conveyor upon which they are supported. However, if the movement of preceding bundles is arrested, each given bundle, upon reaching the obstruction, will likewise come to rest and the rollers 11 of the conveyor will rotate therebeneath without propulsion effect upon the arrested bundles. As soon as the obstruction is removed, the bundles will resume their forward movement with the conveyor.

The input conveyor generically designated by reference character 2 delivers the bundles or other workpieces on to conveyor work table 12, this table constituting a portion of the feeder whereby the bundles are transferred from the conveyor to the tying machine as rapidly as they can be handled by such machine. Feed rolls 13 are journaled in the table 12 and provided with shafts at 14 equipped with sprockets 15 driven by chain 16 from the motor 17. Idler sprockets 18 between each pair of sprockets 15 hold the chain 16 to the sprockets 15 to assure the positive operation thereof. At the end of the feed table 12 toward which the bundles are delivered during operation of roller 13, there is a stop plate 19 which, upon being engaged by a bundle, opens the normally closed switch 20 in the circuit of motor 17 to arrest the operation thereof.

When a bundle comes to rest by reason of its engagement with the stop plate 19, it is directly in the path of the ram 25, which is shown in retracted position in full lines in Fig. 2 and in advanced position in Fig. 3 and dotted lines in Fig. 2.

The ram, generically designated by reference character 25 comprises a head 26 carried by a skeletonized frame or carriage which may conveniently include two laterally spaced upper arms 27, 28 and correspondingly spaced lower arms 29, 30, all of which project rearwardly from the ram as shown in Figs. 2, 3 and 5. Intermediate their ends, the lower arms 29 and 30 carry grooved wheels 31, 32, respectively, which operate on the lower rails 33, 34 of a guideway provided by the machine frame. Near their rear ends, the rearwardly extending arms 29, 30 carry another set of grooved wheels 35, 36 which engage the upper rails 37, 38 respectively of the said guideway, being held thereto by the weight of that portion of the ram and the said arms which extends forwardly of the supporting wheels 31, 32.

The upper arms 27, 28 carry cam means for actuating controls in a manner hereinafter to be described.

The ram is advanced and retracted in any desired manner, preferably pneumatically. A pneumatic cylinder 39 has its rear end fixed in a cross member 41 of the frame. The plunger 40 which operates in the cylinder is connected at its forward end with the work propelling head 26 of the ram. As will hereinafter be explained, there are pneumatic connections to both ends of the cylinder so that the piston 42 connected with plunger 40 may be subjected to pressure in either direction to advance or retract the ram as desired.

When the ram advances from the full line position of Fig. 2 toward the dotted line position thereof, it will push the workpiece or bundle a half or one-third of the way across a tying slot

44 in the tying machine 3. This machine has a table 45 registering with the rollers 13 to receive the bundle from the rollers when the bundle is pushed across the ends of the rollers by the advancing ram. As explained above, in connection with the statement of the objects of this invention, it may be desired to provide the bundle with a single tie, in which case I am able to control the ram in such a manner that it stops short of the dotted line position shown in Fig. 2 to leave the bundle disposed symmetrically centered with respect to the slot 44 in which the tie is manipulated to tie the bundle. Alternatively, the ram may be caused to arrest the motion of the bundle in a first position in which the original tie 46 is applied to the bundle, whereupon the ram advances further to the dotted line position of Fig. 2 where the bundle is positioned to receive its second tie 47 (Fig. 9).

Each tying operation of the tying machine is initiated conventionally by a pedal 48 (Figs. 2, 3, 4 and 5). Each time the pedal is depressed, the tying machine will make one tie about the workpiece or bundle therein. It is unnecessary to change in any manner this conventional operation of the tying machine but it is desired to provide means for correlating this operation, and controlling it with reference to the operation of the feeder so that the feeder will supply bundles as rapidly as the tying machine can act thereon, up to the capacity of the tying machine and the infeed conveyor respectively. To this end, the frame of the feeder 4 carries at its forward end a plate 49 which mounts a solenoid 50, the armature plunger 51 of which is connected by link 52 with a lever 53 having a free end portion provided with a foot at 54 engaging treadle 48.

I shall now describe the fluid connections for powering the ram, after which I shall describe the electrical controls for the pneumatic power and electrical power.

There is an air supply line 55 and an air exhaust line 56 which lead to and from the casing of the four-way valve 57. One port 58 of such valve communicates, subject to another solenoid operated check valve 59, with a pipe 60 leading through the exhaust valve 61 and pipe 62 to the closed end of cylinder 39.

Another port 63 of the four-way valve 57 communicates through pipe 64, subject to the control of solenoid valve 65 and a regulating check valve 66, with pipe 67 which leads to cylinder 39 near the end through which the plunger 40 operates. The solenoid valve 65 is bypassed by a line 68 in which there is a regulating valve at 69 and a solenoid valve at 70, these being adapted to control the return flow to exhaust, and thereby to regulate the speed of advance of the plunger 40 which propels the ram 25.

Similarly, in the line which goes to the closed end of the ram cylinder 39, there is a bypass 71 from exhaust valve 61 to the exhaust pipe 56 under the control of the needle valve 72.

The four-way valve 57 is operated in one direction by a spring 73 and in the other direction by a solenoid 74. The normally closed valve 59 is opened when its solenoid 75 is energized. The normally closed valve 65 is operated when its solenoid 76 is energized, and normally closed valve 70 is operated when its solenoid 77 is energized.

The valves 66, 69 and 72 are merely adjustable throttle valves, the throttle valve 69 being set to a smaller aperture than the throttle valve 66 so that when these throttle valves are connected in series by the opening of solenoid valve 70 and the

closing of solenoid valve 65, the return flow from the cylinder will be slower, and the movement of the plunger more retarded, than when valve 65 is open.

The valves used at 61 and 69 may be conventional. Valve 61 may be like the valve of Vorech Patent 2,040,580 and valve 69 may be like the valve in Schrenk Patent 2,417,217.

The arms 27, 28, 29 and 30 which project rearwardly from the ram head 25 not only guide the ram but constitute a carriage. Supported on the upper arms 27 and 28 is a cam plate 79 (Figs. 2 and 4) which, in the advance of the ram moves beneath the fixed plate 80 upon which are mounted switches 81, 82, 83, 84 and 85, each comprising a cam follower lever 86 (Fig. 2 and Fig. 6) operable by the cams 86, 87, 88, 89 and 90 on plate 79. There is also a limit switch 91 having its arm 92 positioned to be engaged by operating lug 93 carried on arm 29 of the ram. There is a master switch 930 and a selector switch 94 (Figs. 3 and 4). The manner in which these several switches are desirably connected for the control of the operating mechanism is diagrammatically shown in Fig. 10 and in the table of Fig. 11, wherein the effect of the various positions of the selector switch is indicated.

Referring to Fig. 10, it will be noted that the motor 17 is supplied with current by a three-phase circuit from which power is taken off through the main supply line 117 and to which the power is returned through the main return line 118. The actual functioning of the motor 17 is controlled by relay switch 119.

In addition to the selector 94, which has four sets of contacts at A, B, C and D, there is another selector at 120 which has six sets of contacts marked E, F, G, H, I and J. This selector has for its sole function the determination whether the bundle is to be fastened with a single tie or a double tie operation.

The selector 94 has five positions, permitting the operator to set the device for automatic operation, wherein the tying machine is automatically operated synchronously with bundle feed, or manual operation in which the bundle feed continues to operate but the tying machine does not, or for forward or reverse operation of the ram independently of any other functioning of the apparatus, this being desirable in order that the machine may be serviced. For example, odd sheets of paper may become separated from the bundles and lodged in the path of the ram, thus requiring separate ram manipulation to clear the machine. The table in Fig. 11 shows which of the several contacts of selector 94 are closed when the selector is set in one or another of its operative positions. Thus in the selector position which causes forward propulsion of the ram only, the contacts B are the only ones which are closed. For manual operation, contacts A and C are closed. For automatic operation, the contacts A, C and D are closed. In the off position of the selector switch, all contacts are open.

There is an emergency circuit breaker at 121 which, when operated, stops the entire machine. The other components of the electrical circuit can best be described in connection with a description of the specific operation. The selector switch 120 which determines the number of ties is shown in the position which it occupies for a single tie operation, the contacts at E, G and I being closed and the other contacts open.

With the selector 94 set for automatic operation, the leading bundle on the conveyor 2 ad-

vances therefrom on to the rollers 13 which are being operated by the motor 17. When such bundle reaches the arm 19 of stop switch 20, it displaces this double throw switch from the full line position to the dotted line position shown in the diagram of Fig. 10. This immediately opens the circuit of the motor controlling relay 119, permitting the motor 17 to stop the operation of feed rolls 13. This leaves the bundle at rest in the path of the ram 25.

In its new position, the switch 20 closes a circuit to relay 122 which has two sets of contacts. The first contact at 123 controls a holding circuit which maintains this relay closed so that its second contact at 124 may energize the actuating solenoid 74 of the four-way valve 57, the connection being made from the main supply line 117 through the contacts A of the selector switch 94 to solenoid 74 and thence through the return line 118.

The movement of the four-way valve to the position shown in Fig. 2 permits air to flow from the supply pipe 55 through the open solenoid valve 59 and through the double acting check valve 61 to the closed end of the cylinder, thus forcing the ram plunger 40 forwardly to advance the ram 25, thereby propelling the bundle from rollers 13 on to the table of the tying machine. In thus advancing, the piston 42 of the ram plunger displaces air from the other end of the ram cylinder and such air must return to exhaust through the pipe 67 and the regulating valve 68, the solenoid valve 65 being open. Upon reaching the four-way valve, the air passes from port 63 to the discharge pipe 56 as shown in Fig. 2.

As soon as the carriage starts forward, the limit switch 91 opens. This switch continues to hold the motor 17 idle, even after the advancing bundle clears the bundle operated switch 20, which switch closes as soon as the bundle passes out of contact with the arm 19. The holding circuit for relay 122 is required for the same reason.

As the carriage reaches the desired forward position in which the bundle is centered over the slot 44 of the tying machine, the cam 90 on the top of the carriage operates switch 85 which is in the holding circuit for the relay 122, thus opening this relay. This deenergizes the solenoid 74 of four-way valve 57, whereby the spring of such valve returns the valve to its initial position and reverses the air connections. At the same time, the cam 89 on the carriage operates the switch 84 which energizes the relay 125, this in turn energizing the coil 50 of the solenoid which operates the foot 54 for depressing the treadle 43 to initiate movement of the tying apparatus.

When the four-way valve 57 reverses, air from the supply line 55 passes through port 63 and pipe 64 and the speed controlling check valves to the outer end of the cylinder, where it acts on the front of the piston to reverse and retract the ram. The exhaust air from the closed end of the cylinder flows through valve 61, pipe 74 and control valve 72 to the exhaust pipe 56. The needle valve controls the retractive movement of the plunger and ram. As soon as the carriage reaches its retracted position, switch 91 is again closed to energize the motor 17 and start the conveyor rolls 13 into operation to bring a new bundle into position before the ram.

Where a double tie is to be made, the secondary selector switch 120 is thrown to open the contacts at E, G and I and to close those at F, H

and J. As before, the bundle advances over rollers 13 until it strikes the arm 19 to close the switch 20 which arrests the rotation of rolls 13 and throws the four-way valve 57 to initiate the forward movement of the ram.

When the ram plunger reaches the proper position for the first of the two ties to be made as shown in Fig. 8, the bundle being advanced about a third of the way across the tying slot 44, the switch 81 is shifted by the cam 88 from the full line position of Fig. 10 to the dotted line position in that view. The opening of the circuit normally closed by this switch breaks the circuits to the solenoids of valves 65, 59 and 70, allowing all of these valves to close, thereby trapping the air on both sides of the piston in the ram cylinder. This immediately stops the advance of the ram. Switch 81 also energizes the time controlled relay 127 which, by reason of its time control mechanism, does not close for a period which, in the instant machine, is two and one-half seconds, this being the time required for the tying machine to perform its cycle. The effect of the closing of this relay will be described later.

The movement of the carriage to the position in which the first tie is made also causes the cam 88 on the carriage to operate switch 83. This switch, now being in circuit by reason of the closing of the contacts J of the secondary selector switch 128, energizes the relay 128 which is also time controlled. In this instance, the time control holds the relay closed for a period which, in the instant device, is approximately one second. The closing of the switch 128 controlled by this relay, energizes relay 125 which, as already described, energizes the solenoid 50 which operates the tying machine. The period of one second for which the solenoid remains energized is predetermined to be adequate for the pedal to initiate tying machine operation.

As above noted, the operation of the tying machine as thus initiated will continue for about two and one-half seconds to perform the first tie about the bundle. At the conclusion of that period, the relay 127 acts. When it acts, a switch is closed at 131. The closing of the switch at 131 energizes the solenoids 75 and 77 of valves 59 and 70 but the previous opening of the switch at 130 prevents the solenoid 76 of valve 65 from being energized. In consequence of these valve controlling operations, air is again admitted to the closed end of the cylinder to advance the ram and the further advance of the ram is controlled to a slower rate than that originally permitted, the air from in front of the ram piston being now forced to exhaust through the regulating valve 69, valve 65 remaining shut. The reason for this is to avoid projecting the partially tied bundle past the proper position for the final tie.

Before a bundle is tied, its friction upon the table is much higher than the friction of the same bundle after one tie about the bundle has been made. Accordingly, if the same amount of energy were exerted on the bundle after tying as was required to propel it previous to the making of the first tie, the bundle would be thrown through the tying machine without stopping at the required point. The arrangement described makes it possible to set the control valve 66 at a value such that it will determine the initial movement of the bundle before any tie has been made, while, after a tie has been made,

the control of valve 69 will become effective to reduce the rate of operation.

When the bundle reaches the desired position for the second tie, cam 89 in the carriage 5 operates the switch 82, which opens to break the holding circuit to the relay 122 and thereby to deenergize the solenoid 74 of the four-way valve 57, which now moves from the position shown in Fig. 2 to the position which permits the ram plunger to be retracted. In the return movement of the ram, cam 88 again acts on the follower of switch 83 which once more energizes relay 128 to close contacts 129 for a period sufficient to energize relay 125 and solenoid 50 to depress the pedal control 48 for initiating the final tying cycle of the tying machine. As before, the movement of the ram carriage to its retracted position engages switch 91, resulting in the further movement of the motor 17 which drives the conveyor rolls 13 and advances another bundle.

The operation of the pneumatic and electrical mechanisms and interlocks above described may be summarized as follows:

As bundles are advanced over the conveyor 2, the foremost bundle will be further advanced by the motor driven rolls 13 provided the space in front of the ram is clear. If the rolls 13 are already occupied by a bundle, the rolls will be at rest and bundles arriving on conveyor 2 will be stopped and the conveyor will pass idly beneath them.

As the foremost bundle advances over the power driven rolls 13, it will ultimately strike the limit arm 19 which will stop the operation of these rolls, leaving the bundle in front of the ram. In deenergizing the motor which drives rolls 13, the switch 20 will also establish the proper connections for the pneumatic advance of the ram to propel the said bundle longitudinally of rolls 13 and across the table of the adjacent tying machine to a position to receive a tie. This position may be varied by the operator according to whether one tie or two ties are to be made about the bundle.

In either case, the bundle will come to rest at the proper point on the tying machine and through electrical interlocking means above described, a solenoid operated foot on the conveyor mechanism will actuate the pedal on the tying machine to make a tie about the bundle. Meantime, the ram has been retracted and, through the electrical interlock, the retraction of the ram results in the energization of the motor for advancing another bundle into position before the ram.

If a double tie is being made, the ram will not be retracted until after it has made a second advance sufficient to reposition the bundle for the second tie, after which the operation is the same as above described. In that case, the movement of the ram is automatically controlled in its advance toward the position for the second tie to avoid overshooting the proper bundle position.

The power of the ram is such that as each bundle is advanced, it pushes from the tying machine the bundle previously tied therein.

Thus, the bundles are advanced as rapidly as the tying machine is able to handle them and the tying machine is automatically caused to operate as rapidly as the bundles can be positioned therein. The entire operation is automatic with no time lag beyond that required for the movements of the bundles, and no attention required of the operator.

I claim:

1. The combination with a machine for acting on a workpiece and a first control for initiating its cycle of operation, of feeding mechanism comprising a feed conveyor constituting power driven supporting means, a power source having driving connections to said supporting means and having a drive interrupting second control, a transfer ram having a guiding carriage, ways for said carriage disposed transversely of said feed conveyor and toward said machine, actuating means for said ram including a third control, a work operated stop means to actuate the second control, connections from said stop to said third control for initiating ram movement in a direction to advance a workpiece from said supporting means toward said machine, ram operated means for arresting ram movement in a predetermined position of advance thereof in which said workpiece is delivered to said machine, and means for actuating the first control upon the arrival of the workpiece at said machine, said second control being normally in a position to permit resumed operation of said supporting means after said ram and workpiece have passed thereover.

2. A feeder for controlling the operation of a bundle tying device and delivering bundles thereto in synchronism with the operation of said device, said feeder comprising the combination with a conveyor having power operating means provided with a first control, a ram, a guideway in which the ram is operable transversely of the conveyor and toward said device, said ram having actuating means provided with a second control separately effective to preclude conveyor movement, said feeder having a third control for initiating a predetermined cycle of tying operation, means for actuating the first control to arrest conveyor movement and comprising a yieldable stop disposed in the path of bundle movement upon the conveyor, said stop being engageable by a bundle positioned in front of said ram, such stop normally being in a position for the initiation of ram movement, ram operated means for arresting ram movement upon delivery of the bundle to the tying device, means for operating the third control to effect operation of said tying device upon such delivery, means operated by said ram for effecting ram retraction, and means effective upon the retraction of the ram for actuating the second control for resumption of conveyor movement in a direction to position another bundle in front of the ram.

3. The device of claim 2 in which said actuating means of the ram comprises a pneumatic cylinder and piston, the said cylinder having pneumatic connections and valves for the control thereof, said valves having electromagnetic means for their operation, together with a fourth control comprising an electric switch in series with such electromagnetic means and comprising an operating member for which said piston is provided with an actuator engageable with the switch operating member at an intermediate point in the stroke of the ram to close the valve controlling the pneumatic connections and thereby to arrest ram movement.

4. A device of the character described comprising the combination with a power operated feed conveyor, an electric motor in driving connection with such conveyor, and a switch in circuit with the motor for controlling conveyor operation, of a stop in the path of workpieces pro-

5 pelled by said conveyor, said stop being connected with said switch for the opening thereof to arrest conveyor movement when the stop is engaged by a work piece, a ram operable transversely of said conveyor in a direction to engage a workpiece which has operated said stop for the lateral discharge of said workpiece from the conveyor, a plunger connected with the ram, a cylinder in which said plunger is operable, fluid connections to said cylinder provided with reversible electromagnetically operable valve means, an electrical circuit controlled by said stop for opening said valve means for the advance of said ram, and ram operated means for reversing said valve means for the return of said ram after a predetermined advance of said ram, said cylinder having fluid control connections provided with an adjustable throttle valve for regulating the rate of ram movement in one direction.

20 5. For use with a bundle tying machine having a predetermined cycle of operations and a control for initiating such cycle, a feeder for the synchronized feeding of bundles to said machine and for synchronized actuation of said control, said feeder comprising a work propelling ram, electrically controlled means for the advance and retraction thereof between a first retracted position, a second intermediate position, and a third advanced position, and switches controlling said means including first and second switches in the path of advance of the ram, switch operating members carried by the ram and respectively operable upon the first and second switches at said second and third positions of the ram for arresting ram movement, and a circuit including a control switch for selecting which of said first and second switches will be operative to arrest ram movement, whereby the ram may be caused to stop at selected points, said circuit including electromagnetic means for operating said control of said tying machine when said ram has advanced to one of said positions.

30 6. The device of claim 5 in which the second position of the ram is the position in which the said electromagnetic means operates the tying machine as aforesaid, in further combination with circuit means for causing the ram to dwell in the said second position and thereupon to resume its advance to its said third position, said ram and circuit including coating members for operating the said control of said tying machine again in said third position.

35 7. The device of claim 6 in which the electrically controlled ram operating means comprises a cylinder, a plunger valve, controlled fluid connections to the opposite ends of the cylinder, a fluid supply line, valve means for connecting said lines alternatively to the opposite ends of the cylinder, and valve means in the respective lines including check valves for freely passing fluid to the cylinder for the operating stroke of said ram and for controlling restricted flow of fluid from the opposite end of the cylinder for regulating the rate of ram operation.

40 8. The device of claim 7 in which each of the lines from the cylinder includes a bypass, one of said lines having one flow restricting valve and a bypass therefor having another flow restricting valve, and a selecting valve for determining whether return flow from the cylinder will traverse the bypass.

45 9. In a device of the character described for the synchronized delivery of bundles to a tying machine and the synchronized initiation of a cycle and tying machine movement, the combi-

11

nation with a ram and a ram carriage, of ways upon which the carriage is reciprocable for the guidance of the ram for movement to and from the tying machine, a conveyor operable transversely of ram movement when delivering successive bundles into the path of the ram, cams connected with the carriage, switches mounted to be actuated by the several cams in the course of ram movement, and ram actuating means having electrical controls, and circuit means selectively connecting said switches to said controls and determinative of which of said controls will operate, one of said controls being adapted to arrest ram advance in one position and another of said controls being adapted to arrest ram advance in a different position.

10. The device of claim 9 in which said ram is provided with an operating plunger and a cylinder in which the plunger is reciprocable, the cylinder having a pneumatic system for admitting and withdrawing air to and from the respective ends thereof, and electromagnetically controlled valves for controlling flow of air to and from the respective ends of the cylinder.

11. The device of claim 10 in which said pneumatic system includes an air exhaust line having an adjustable throttling valve for regulating the flow of air therethrough and hence regulating ram movement in one direction, said line further including a bypass and valve means for determining selectively the flow of air as between the bypass and the throttling valve.

12. In a feeder for operation in synchronism with a tying machine and operable to deliver bundles to said machine to receive single and double ties according to the position of delivery, the combination with a ram having a plurality of switch operating cams, of operating connections for the ram provided with a plurality of switch

12

controls, one of said switch controls being adapted to arrest ram movement in a first position for a single bundle tie, another of said switch controls being adapted to arrest ram movement in a second position for the first of two bundle ties, and a third of said switch controls being adapted to arrest ram movement in a third position for the second of two bundle ties, a circuit to the ram actuating connections including a selector switch for coupling particular switches selectively into said circuit, and means for initiating tying machine operation when the movement of the ram is arrested, irrespective of the position in which ram movement is arrested according to which of several control switches is in circuit.

13. The device of claim 12 in further combination with a bundle input conveyor for positioning successive work bundles before said ram, actuating connections for said conveyor, and means operatively connected in said circuit for automatically actuating said conveyor for the delivery of successive bundles before said ram upon each retraction thereof and for initiating ram advance after the successive bundles are positioned before the ram.
